UNITED STATES PATENT OFFICE.

BENJAMIN D. TRAITEL, OF NEW YORK, N. Y.

DESIGN FOR A FINGER-RING.

SPECIFICATION forming part of Design No. 14,247, dated August 28, 1883.

Application filed May 3, 1883. Term of patent 3½ years.

To all whom it may concern:

Be it known that I, BENJAMIN D. TRAITEL, a citizen of the United States, and a resident of New York city, in the county of New York and State of New York, have invented and produced a new and original Design for Finger-Rings, of which the following is a specification, reference being had to the accompanying drawings, forming part thereof.

- 10 This invention relates to a novel design for finger-rings; and it consists in various features of configuration and ornamentation, which will be hereinafter more fully described, and particularly pointed out in the claims.
- 15 In the accompanying drawings, Figure 1 is a top plan view of a ring embodying my invention. Fig. 2 is a side elevation of the same, and Fig. 3 a vertical cross-section taken at the line α α of the first-named figure.
- 20 The same letters of reference indicate the same parts in the several views.

A is the shank or hoop of the ring, and B the setting thereof, to which latter my invention has particular reference. This setting 25 B, I form of any suitable material, and produce therein a central depression or sunken portion, b , and onto the outer surface of this depressed part I mount or arrange an ornament—as, for example, an initial letter, a .

30 In the case in which I have illustrated my invention I have shown the setting B rectangular in outline and curved in form, and I have shown that portion of the setting immediately surrounding the depression b corrugated or fluted in contour and of an elliptical shape. The uppermost surface of the setting B, or that portion lying in a plane above that of the part b , I have ornamented with radiating lines or rays, as seen at e .

40 Contiguous to the setting B, and on either side thereof, the shank A is made flaring, and is formed with several V-shaped notches, f , producing a serrated edge, from which extend downwardly obliquely-engraved lines n , meeting perforations m in the shank of the ring.

Although I have shown the depression b decorated with the letter T, it is apparent that any other raised letter or ornament may be used in lieu thereof.

50 The ornament a , I make of a thickness equal

to the distance between the uppermost portion of the setting and the top surface of the depression b , or, in other words, equal to the depth of the depression b , so as to bring the top face of the ornament about flush with the 55 uppermost or outer face of the setting B; and in practice I have in some instances made the ornament a in two colors by the well-known method, which renders the setting, as a whole, still more handsome and effective in 60 appearance.

What I claim as my invention, and desire to secure by Design Letters Patent, is—

1. A finger-ring having substantially the configuration and ornamentation shown and 65 described.
2. A finger-ring setting having a central depression and a raised ornament therein, the wall of the setting surrounding the depression being corrugated or fluted, as shown and 70 described.
3. A finger-ring setting having a central depression and raised ornament therein, the top surface of the setting being ornamented with radiating lines or rays, substantially as shown 75 and described.
4. A finger-ring setting having a central depression and a raised ornament therein, the wall of the setting being corrugated or fluted, and the top or uppermost surface of the setting 80 ornamented with radiating lines or rays, substantially as shown and described.
5. A finger-ring setting, rectangular in outline, having a central depression of elliptical form, and a raised ornament therein, substantially as shown and described. 85
6. A finger-ring having a setting with central depression and raised ornament therein, and serrated shank ends, substantially as shown and described. 90
7. A finger-ring having a setting with central depression and raised ornament therein, and serrated shank ends, and ornamentation n m , substantially as shown and described.

In testimony whereof I have hereunto set 95 my hand this 1st day of May, 1883.

BEN. D. TRAITEL.

In presence of—

JACOB DU BOIS,

JACOB FELBEL.
